UNITED STATES PATENT OFFICE.

EDWIN WRIGHT, OF LONDON, ENGLAND.

ORGAN.

No. 912,767.

Specification of Letters Patent.

Patented Feb. 16, 1909.

Application filed July 19, 1907. Serial No. 384,618.

To all whom it may concern:

Be it known that I, EDWIN WRIGHT, a subject of the King of Great Britain, residing at 654 Holloway road, London, England, have invented new and useful Improvements in Organs, of which the following is a specification.

My invention relates to organs of the kind wherein the bellows are operated by the feet of the player, the object of my invention being to provide in conjunction with the treadles means whereby a performer can play a pedal part to the music with both feet while at the same time the feet are engaged 15 in blowing the bellows of the instrument.

According to my invention I combine with the treadles or footboards of the instrument a series of key levers or abutments which are connected by suitable mechanism 20 with the reeds or pipes of the manual or with an independent set of reeds or pipes, the movement of the said levers or abutments being operated by pushing the feet against them.

25 In the accompanying drawings:—Figure 1 is a sectional side view showing so much of an American organ as is necessary to illustrate the application of my invention. Fig. 2 is a sectional side view showing the mechanism in connection with the bellows treadle drawn to a larger scale than Fig. 1. Figs. 3 and 4 are respectively a plan view and an underside view of one of the treadles, showing the arrangement of the key-levers there- 30 on and some of their connections. Fig. 5 is a view of a detail. Fig. 6 is a plan view illustrating a modification of my invention wherein the treadle levers are arranged in conjunction with a series of reeds independ- 35 ent of the manual, and Fig. 7 is a plan view of a portion of Fig. 6 drawn to a larger scale and embodying certain details not shown in the latter figure. Figs. 8, 9 and 10 are sec- 40 tions on the lines 8—8, 9—9 and 10—10 re- 45 spectively of Fig. 7. Fig. 11 is a view of cer- 50 tain parts shown in Fig. 10 but in a different position.

55 *a* indicates the keys of the instrument, *b* the reservoir bellows, *c* the exhausters and *d* a treadle for operating the said exhausters, these parts being arranged in the usual manner. *e*, *e*⁰, *e*¹, *e*², *e*³, *e*⁴ are a series of spring key-levers which are mounted on the said treadle by means of pivot pins *f* which ex- 60 tend through the treadle to the undersides thereof, the said levers being arranged in

such positions that the movement of the foot forward or backward or of the toe or heel in a lateral direction to either side will cause the movement of one of the said key-levers such as movement being limited by stop pins *e*^x, *e*^x. The pivot *f* of each of the key-levers has attached to it beneath the treadle an arm *g*, the free end of which is connected to one end of a double armed lever *g*², the other end of which extends down into a position adjacent to the hinge *h* of the treadle. The connection between some of the arms *g* and the levers *g*² is effected by links *g*¹, and also by a pin and slot *g*⁰ as shown clearly in Fig. 4. 70

Upon the base of the casing *a* is pivoted a series of double armed levers *i* with which the several double armed levers *g*² respectively coöperate, each lever *g*² being at its end nearest the hinged joint of the treadle pro- 75 vided with a lug or extension *j* coöperating with a lug or extension *k* on a lever *i* so that when the lever *g*² is moved laterally the lever *i* will also be swung laterally upon its pivot. It is to be understood that the size and posi- 80 tions of the lugs *j*, *k* are such that they will always be in contact notwithstanding the movement of the treadles. It is to be understood that the treadle should be in its depressed position, when the valves are 85 operated. The lever *i* at its rear end bears against one arm of a bell-crank lever *l* as shown clearly in Fig. 5, the other arm of which lever has connected to it one end of a sticker *m*, the upper end of which is jointed 90 to one end of a lever *n* which at its other end is arranged in conjunction with a pallet or valve of a reed of the manual as will be clearly understood by reference to Fig. 1. With this arrangement it will be understood 95 that the movement of either of the key-levers *e*, *e*⁰ etc. can be communicated to the corresponding pallet.

Instead of the parts *i*, *k*, *l*, *m*, *n* for actuating the pallets I may employ pneumatic con- 100 nections; the movements of the extensions *j*, *j* coöperating with the valves governing the admission of air to tubes or channels connected with corresponding pallet motors in a well known manner.

105 In order to allow of readily moving the foot in contact with either of the key-levers it is necessary to provide for momentarily locking the treadles against upward movement on their hinges and this I advanta- 110 geously accomplish in the following manner: To the underside of the foot-board *d* I rigidly

attach a pneumatic chamber o preferably of bellows form, as shown in Figs. 1 and 2; the bottom board o^1 of which is held in a practically fixed position so that during the oscillation of the treadle the pneumatic chamber will be alternately filled and emptied. In the drawing I have represented the said bottom board o^1 as provided with an extension o^2 which passes between rollers o^3, o^3 carried in the framing and which allow of any slight movements of the extension due to the fact that the hinged joint of the pneumatic chamber does not coincide with the hinge of the treadle. The upper board or part of the air chamber o is fitted with two valves p, p^1 , the former of which is an ordinary flap valve which at all times allows the air in the chamber to escape when the foot-board is pushed downward. The other valve p^1 is of the hinged or pallet variety and is closed in the ordinary way by a spring p^3 . This valve p^1 has arranged in connection with it a short rod p^3 which passes through the treadle d and projects slightly above the same.

Upon the treadle d is a foot-plate q capable of a slight rising and falling motion relatively to the treadle. The foot-plate q may be hinged to the footboard at any convenient part for instance as shown at q^0 or it may lie freely in the recess provided for it, and be kept in position laterally by two or more loosely fitted dowel pins. This foot-plate, in the drawing, is represented as being shaped to the sole of the foot but it may be of any other convenient shape and may occupy the whole of the available space between the key levers e, e^0 , etc. The said footplate q is acted upon by a spring q^1 , the power of which is so regulated that during the movement of the treadles by the performer the said foot-plate q will be pressed downwards so as to hold the valve p^1 open and allow free ingress and egress of air into and from the pneumatic chamber o whereby the latter will not offer any impediment to the free operation of the footboard.

When the performer desires to operate one or other of the key-levers he first raises his foot sufficiently to take the pressure off the foot-plate q so that the spring q^1 will raise the said plate and allow the valve p^1 to close under the action of its spring p^3 . The result of thus closing the valve p^1 will be to prevent the air from entering the pneumatic chamber o whereby it will be obvious that the top board of the chamber and also the treadle d will remain stationary until the operator again presses upon the plate q to open the valve p^1 .

The groups of key-levers e, e^0 &c. and the plates q on the footboards may be inclined or "splayed" to suit the natural outward inclination of the feet.

It is to be understood that the invention

is not limited to any particular arrangement of the key-levers, as any arrangement of such levers upon the treadles to be operated by the feet may be employed and it is also to be understood, that the number of such key-levers may be increased or decreased as desired. In the arrangement before described I have shown the treadle as provided with six levers so that both treadles would have between them twelve levers corresponding with the twelve semitones of the chromatic scale but when the invention is employed in conjunction with an independent set of reeds I advantageously make use of the arrangement shown in Figs. 7 to 11. In this arrangement I have shown three sets of reeds r, s, t (Fig. 8) of the scales known as 16 feet, 8 feet and 4 feet respectively, the chambers containing the several sets of reeds being adapted to be closed by mutes r^1, s^1 and t^1 respectively. The corresponding reeds of the three sets are controlled by a single valve u which is operated by a sticker m controlled by one of the treadle levers or pneumatically in the manner hereinbefore described, whereby when either of the said treadle levers e, e^0 , &c. is operated, the corresponding valve u will be opened to sound the particular reed of the three sets of reeds the mute of which is raised. The control of these mutes is advantageously effected pneumatically, although they may be otherwise operated. In the drawing I have represented three pneumatic motors r^2, s^2, t^2 which are designed to respectively control the mutes through the medium of levers r^3, s^3, t^3 , each of which is at one end directly acted upon by its motor and at the other end carries a sticker rod which acts against a crank arm on the mute in such a manner that when the corresponding motor is operated the mute will be raised to allow the corresponding set of reeds to sound when the valves or pallets u are opened.

In conjunction with the several motors are passages r^4, s^4, t^4 in the top of the wind-chest v , the said passages being respectively controlled by valves r^5, s^5, t^5 so as to put the motors in communication with the atmosphere. Normally the motors r^2, s^2, t^2 are in communication with the wind-chest by spring valves r^6, s^6 and t^6 respectively arranged on the undersides of the said motors the said valves being held in the open position against the pressure of their springs by extensions v^1 on the undersides of the valves r^5, s^5, t^5 abutting against extensions v^2 on the said valves r^6, s^6 and t^6 . The motors r^2, s^2 and t^2 are normally kept closed by the springs of the mutes acting through the levers r^3, s^3, t^3 .

The control of the several valves r^4, s^4 and t^4 by the performer, is effected through the medium of levers w, x which are placed in such a position relatively with the keyboard that they can be depressed by the fingers or

wrists of the performer either independently or simultaneously. The levers w and x are mounted respectively upon spindles w^1 , x^1 which also carry arms w^2 , x^2 which bear upon 5 a T-piece y . This T-piece y is suspended from the casing by means of a spring y^1 (Figs. 9 and 10), the spring normally holding the said T-piece in the position indicated by the dotted lines in Fig. 10. The vertical leg 10 y^2 of the T-piece coöperates with a pivoted spring arm y^3 which carries the valve s^5 , Fig. 9, and it has also extending in a forked portion through it, a rod y^5 which operates two spring levers w^3 , x^3 which carry the valves 15 r^4 , and t^4 respectively. The rod y^5 slides through holes in the levers w^3 , x^3 and is provided with buttons y^6 so that the said levers can be operated independently. With this arrangement when the performer wishes to 20 raise, say, the mute s^1 , he presses down the levers x , w simultaneously, so that the T-piece y , which is acted upon at the two ends by the levers w^3 , x^3 will be moved down vertically to the position shown in Figs. 9 and 25 10 to lift the valve s^5 , the result of which will be that the suction within the wind chest v will cause the motor s^2 to expand by the pressure of the atmosphere and through the medium of the lever s^3 and the connected 30 sticker rod raise the said mute s^1 so that any of the reeds therein will sound when the respective pallets or valves u , u , are operated by the treadle key-levers. If, on the other 35 hand, the performer desires to raise the mute r^1 he depresses the lever x only, so that the T-piece, instead of being moved down vertically is rocked to one side, as shown in Fig. 11, this movement having the effect of opening the valve r^5 . To lift the mute t^1 the 40 lever w is depressed whereby the T-piece is rocked in the opposite direction to that shown in Fig. 11.

For the purpose of retaining open any mute which has been raised I provide a supporting device in connection with the crank arms of the several mounts. This supporting device, as shown, is in the form of an oscillating plate z which is controlled by a rod z^1 having one end adjacent to the keyboard 45 and at the other end connected to a bell crank lever which in its turn is connected by a link z^2 to the plate. The connection between the rod z^1 and the plate is slotted, as shown at z^4 , Fig. 9, so as to allow of the oscillation of the plate without moving the rod z^1 . When the rod z^1 is pushed back the plate z is thrown out of contact with all the cranked arms of the mutes. If, now, any one of the three sets of reeds is to be used, the rod z^1 is 50 pulled outward so that the plate z will lie against the cranked arms with the result that when either of the said cranked arms is lifted it will oscillate the plate z until the cranked arm rises above it, the said plate 55 then dropping back beneath the said cranked

arm and retaining it raised, as shown in Fig. 9. If, during the operation of playing, the performer for the purpose of extending the effective compass of the pedal keys desires to change from one set of reeds to the other 70 he operates the rods x or w or both together as the case may be, to raise the mute of the particular set of reeds desired, which operation has the effect of moving the plate z so that the mute previously supported thereon 75 will drop while the mute which is being raised will be retained by the said plate, it being understood that the slot z^4 allows of this movement of the mute, the natural tendency of the said plate being to always 80 fall toward the cranked arms. When the plate z is pulled back out of contact with the cranked arms of the mute, it will be understood that either of the mutes may be momentarily raised and then lowered by the operator to allow of the sounding of a reed in any of the three sets, or the three mutes may be raised simultaneously, and held open by an ordinary draw-stop action.

Having now particularly described and 90 ascertained the nature of my said invention and in what manner the same is to be performed, I declare that what I claim is:—

1. In an organ, the combination with a treadle of pneumatic means for holding the 95 treadle from movement when desired, substantially as described.

2. In an organ, a treadle provided with a bellows beneath the same, a passage for admitting air to the interior of the bellows, a 100 valve for controlling said passage and a foot plate for controlling said valve, substantially as described.

3. In an organ, the combination with a treadle, of an air-compression device connected with and operated by said treadle, a 105 passage for admitting air to said air-compression device, a valve for controlling said passage and a foot plate on said treadle and connected with said valve for opening and 110 closing the same, substantially as described.

4. An organ comprising a treadle, means for holding the treadle in its depressed position, means for producing a tone independently of the manual, a valve for controlling 115 said tone-producing means, and means for operating said valve, including a lever mounted on said treadle and adapted to be operated by the foot on the treadle, substantially as described.

5. In an organ, the combination with a treadle, of means for holding the treadle in its depressed position and means for producing a tone independently of the manual, a valve controlling the same and means for 125 operating said valve said valve-operating means and said holding means being located on said treadle and adapted to be operated by the foot of the operator, substantially as described.

6. In an organ, the combination with a treadle, of an air-forcing device connected with said treadle, a valve controlling the admission of air to the air-forcing device for holding the treadle in its depressed position, means for producing a tone independently of the manual, and a valve controlling the same the said construction including a lever on the treadle for actuating the tone-producing valve and means for closing the air-admission-valve to said air-forcing device, said last named means and the lever being adapted to be put into operation by the foot of the operator, substantially as described.

15 7. A pedal bass organ having a treadle provided with key levers, said key levers being adapted to be operated by the foot of the operator, and a series of levers connecting each of said key levers with tone-producing 20 devices, substantially as described.

25 8. A pedal bass organ having a treadle provided with a series of key-levers, arms on the underside of the foot-plate of the treadle rigidly connected with the key levers, a series of levers connecting said arms with tone-producing devices of the organ, substantially as described.

30 9. A pedal bass organ having a treadle, the foot-board of which is pivoted at one point, a bellows secured to the underside of said foot plate having the top and bottom boards of the same hinged at a point in rear of the pivot of the foot board, said bottom board being provided with an extension 35 passing between rollers whereby provision is made for the movement of the bottom board and the bellows in operating the treadle, substantially as described.

40 10. In a reed organ, the combination with a plurality of independent sets of reeds, of valves one for corresponding reeds of each set, and mutes, one for all of the reeds of each

set, said valves and mutes controlling the passage of air to all the reeds of these independent sets, manually controlled means for moving said mutes, the treadles of the organ and means connected with the treadles, adapted to be operated by the foot of the operator for actuating said valves, substantially as described.

50 11. A pedal bass organ having a manual a plurality of sets of reeds independent of the reeds controlled by the manual, mutes for silencing said independent reeds, manually controlled means for opening said mutes, means for holding the mutes open and manual means for releasing the mutes from the holding devices, substantially as described.

55 12. A pedal bass organ having a treadle 60 provided with key-levers and connections between said key-levers and tone producing devices, of a plurality of sets of reeds independent of the tone producing devices controlled by the manual, a single valve for 65 corresponding reeds of each set, the said organ having also connections whereby the key levers of the treadle can operate the valves of the independent sets of reeds, substantially as described.

70 13. A pedal bass organ having treadles provided with key levers connected with the tone-producing devices, a plurality of independent sets of reeds independent of the said tone producing devices, the said organ having also connections whereby they may be operated from the key levers on the treadles, mutes for the independent sets of reeds and manual means for controlling said mutes, substantially as described.
